UNITED STATES PATENT OFFICE.

PETER DECH, OF WEST ORANGE, NEW JERSEY, ASSIGNOR OF ONE-HALF TO HENRY G. ROLLPILLER, OF WEST ORANGE, NEW JERSEY.

HORSESHOE.

No. 900,268.

Specification of Letters Patent.

Patented Oct. 6, 1908.

Application filed January 15, 1908. Serial No. 410,950.

To all whom it may concern:

Be it known that I, PETER DECH, a citizen of the United States, residing at West Orange, in the county of Essex and State 5 of New Jersey, have invented certain new and useful Improvements in Horseshoes; and I do hereby declare the following to be a full, clear, and exact description of the invention, such as will enable others skilled 10 in the art to which it appertains to make and use the same, reference being had to the accompanying drawings, and to figures of reference marked thereon, which form a part of this specification.

15 This invention relates to an improved calk and means for holding a series of these calks on a horse-shoe so that they are detachable and attachable, and can be put on and taken off quickly and easily.

20 The invention embodies a structure of this kind that provides no obstruction that will enable snow or ice to cake under the horse's hoof, these lumps, when so formed, becoming hard and big enough to raise the calks 25 from the ground and prevent their engagement therewith.

A further object of this invention is to 30 provide clips in which the calks are held, and which the calks in turn assist in holding 35 onto the shoe, and means connecting these calk-clips to normally throw these clips in contact with the shoe, so that if one accidentally becomes loosened it will not come off, and this means also maintains the calk-clips at their required distance from one another.

The invention is illustrated in the accompanying drawing, in which

40 Figure 1 is a bottom view of a horse-shoe with the improved device in place, and Fig. 2 is a section on line 2, 2, in Fig. 1. Fig. 3 is a bottom view of a portion of a shoe showing a modification.

The invention consists in a series of calk-clips 11 which are preferably made U-shaped 45 and have the thinned or beveled portion 12 to fit against the top edge of the shoe, which while giving sufficient bearing surface, is not obstruction enough to prevent its being 50 inserted between the hoof of the horse and the shoe, when the shoe is in place on the hoof. In the side of the clip opposite to the thinned or beveled portion 12, is screwed 55 a calk 13 which has a portion 14 to engage the bottom side of the shoe and while so en-

gaging the shoe, securely holds the calk-clip in place. The calk has a rectangular portion 15 to provide means for engaging it with a wrench or similar tool for turning it, and also has a pointed or otherwise formed end 60 so as to give a ready engagement with ice or hard ground. These calks can be placed too in a calk-clip on the toe of the shoe, as shown in Fig. 1, and this is the preferred form. Smaller calk-clips holding one calk 65 are placed along the sides of the shoe.

Each calk-clip has a perforation 17 therein, in which is fitted the ends of a wire 18, which is suitably bent and has, within itself, a spring action which tends to throw the side 70 calk-clips in contact with the shoe, and also to hold the toe calk-clips in place. These wires 18 also maintain the calk-clips in place if the calks should, by some unforeseen circumstance, become loosened. I prefer to 75 place, on each clip, a lock nut 19 which also holds the calk in place in its clip, and this lock nut is preferably rectangular to give a grasping place to a wrench or similar tool and to also give the calk a generally tapered 80 conformation from its point to the calk-clip. I prefer to use two wires 18, one running from each side calk-clip, and both wires entering the calk-clip that is placed at the toe of the shoe.

In Fig. 3 I show a modification where the 85 shoe is supplied with a permanent toe calk 20, and in this case I prefer to use two smaller calk-clips 11 so disposed as to avoid the toe calk 20, and in this case I may use a 90 single wire 21, suitably bent or forged, to enter these toe calk-clips and having the ends thereof adapted to engage the calk-clips on the side of the shoe. In this view I also 95 show a modified form of the device for holding the calks in the clips, consisting of the set screws 22, the office of these set screws being obvious from the drawing.

Having thus described my invention, what 100 I claim is:—

1. In combination with a horse-shoe, a series of U-shaped calk-clips bridging the inside edge of the shoe, calks on the clips, the clips having perforations on the bottom of the U, and a spring wire bent to form projections 105 to enter the perforations in the clips and held therein by its own spring action, and acting to press the clips toward the shoe and keep them spaced apart, the wire being detachable.

2. In combination with a horse-shoe, a series of U-shaped calk-clips bridging the inside edge of the shoe, calks passing through the clips to secure the clips to the shoe, the clips having perforations on the bottom of the U, and a spring wire bent to form projections to enter the perforations in the clips and held therein by its own spring action, and acting to press the clips toward the shoe and

keep them spaced apart, the wire being detachable and out of contact with the shoe. 10

In testimony, that I claim the foregoing, I have hereunto set my hand this 14th day of January 1908.

PETER DECH.
